UNITED STATES PATENT OFFICE.

IRA W. LEDBETTER AND WILLIAM H. LEDBETTER, OF STONE MOUNTAIN,
NORTH CAROLINA.

DESIGN FOR A CULTIVATOR-SHOVEL.

SPECIFICATION forming part of Design No. 33,858, dated January 8, 1901.

Application filed December 6, 1900. Serial No. 33,973. Term of patent 14 years.

To all whom it may concern:

Be it known that we, IRA W. LEDBETTER and WILLIAM H. LEDBETTER, citizens of the United States, residing at Stone Mountain, in the county of McDowell and State of North Carolina, have invented and produced a certain new and original Design for Cultivator-Shovels; and we do declare the following to be a full, clear, and exact description of the invention, such as will enable others skilled in the art to which it appertains to make and use the same.

The invention relates to a new and original design for cultivator-shovels; and it consists of a design of the shape and configuration shown in the accompanying drawings, in which—

Figure 1 is a front view of the shovel; Fig. 2, a rear view; Fig. 3, a view taken from the pointed end; Fig. 4, a view taken from the opposite end. Fig. 5 is a horizontal sectional view on the line $x x$, Fig. 1. Fig. 6 is a simi-

lar view on line $y y$, Fig. 1; and Fig. 7 is a longitudinal sectional view on line $z z$, Fig. 1.

The leading feature of the design consists of an approximately triangular plate, the converging edges of which are beveled, said plate having in its back near its top a channel 2 and a hole 3 and having its upper corners 4 and 5 curved slightly rearwardly and at its center portion a bulge or spoon-like formation 6.

What we claim is—

The design for a cultivator-shovel as herein shown and described.

In testimony whereof we have hereunto set our hands in presence of two subscribing witnesses.

IRA W. LEDBETTER.
W. H. LEDBETTER.
